UNITED STATES PATENT OFFICE.

EDWARD R. SCHREITER, JR., OF DETROIT, MICHIGAN.

AUTOMOBILE-LOCK.

1,190,469.

Specification of Letters Patent. Patented July 11, 1916.

Application filed April 10, 1914. Serial No. 831,061.

To all whom it may concern:

Be it known that I, EDWARD R. SCHREITER, Jr., a citizen of the United States of America, residing at Detroit, in the county 5 of Wayne and State of Michigan, have invented certain new and useful Improvements in Automobile-Locks, of which the following is a specification, reference being had therein to the accompanying drawings. 10 This invention relates to a safety device for automobiles whereby they cannot be moved under their own power save at the will of the operator while at the same time they can be readily towed or moved out of 15 the garage or other place in case of fire or if it is desirable to shift them a short distance without applying their own motive power.

The invention consists in the matters 20 hereinafter set forth and more particularly set forth in the appended claims.

In the drawings, Figure 1 is a view in longitudinal section of a device that embodies the invention, parts being broken 25 away to give clear view and the same being shown in closed or locked position; Fig. 2 is a view in front elevation of the device partially broken away and with an exterior casing unlocked and removed; Fig. 3 is a view of the back of the device; Fig. 4 30 is a view in side elevation of the device with the casing in position, a valve casing being omitted; Fig. 5 is a view taken on or about line V—V of Fig. 1; and Fig. 6 is a 35 diagrammatic view showing the device installed in proper relation to the ignition system, self starting mechanism and fuel feed supply of an automobile.

Referring to the drawings, a rear base 40 plate 1 carries a pair of guide members 2, herein shown as studs on which a main slide member 3 is longitudinally reciprocable, the slide member having elongated slots as indicated in proper engagement 45 with the guides. A spring finger 4 or other suitably disposed like member normally holds the slide member 3 in retracted position at which time and in which position rock arms 5 and 6 are respectively thrown 50 through engagement of their forked ends 7 and 8 with insulated bushings 9 and 10 on the slide, so that their other arms 11 and 12 respectively close longitudinal gaps on switch blocks 13 and 14. Conductors 15 and 55 15 are connected in series by suitable terminal screws 17 or the like with the switch

block 13 while corresponding conductors 18 18 are similarly connected to the switch block 14. As a result of this arrangement the slide in its normal position establishes 60 electrical connection through the conductors 15, 15 and 18, 18, the former of which may be in series with the battery ignition circuit of a car, while the other 18, 18 are similarly in series with or in the circuit of the 65 magneto or generator system of a car. Such an arrangement is shown diagrammatically in Fig. 6. While it is retracted by the spring member 4, the slide also holds closed a switch that may be conveniently mounted 70 on the back of the base 1 and is of a type suitable for carrying the current of a self starting device.

As herein shown insulated spaced terminals 19 mounted on the slide are adapted 75 to be snapped by the spring 4 into sliding engagement with spaced terminal fingers 20 and thereby close the circuit indicated at 21 through a motor 22 and generator 23, the motor being operatively coupled by suitable means to the engine 24 of the car.

When thus retracted by the spring 4 and in normal position an upturned lug or lateral extension 25 on the slide that is in longitudinal alinement with a spring plunger 85 26 clears the latter so as to allow it to be raised by the abutting contact of a spring projected closure 27. The latter is of the ball type that is seated in a valve casing 28 for which it forms the seal, the casing 90 being supported and attached to the base 1 by a sleeve 29 and clip 30. The sleeve also operates as a housing for the plunger 26 which passes through a suitable packing gland indicated at 32. As herein shown as 95 a convenient form of construction the packing gland has a shoulder 33 whereby it is clamped by the sleeve 29 when the latter is screwed home into the valve casing 28.

The slide is depressed against the action 100 of the spring 4 so as to open the three switch members which it operates and so as to seat the closure 27 by means of a lever 34 that is pivoted on the base 1. A bell crank 35 on the lever abuts the slide 3 and depresses the latter when the lever is moved 105 to the position shown in Fig. 2. When in such position a latch plate 36 is snapped by the action of a suitably disposed spring 37 into such interlocked relation with the slide 110 3 that it retains the latter regardless of any subsequent movement of the lever 34. As

herein shown the notched margin of the latch 36 drops over a lateral projection 38 of the slide. A permutation lock barrel 39 is mounted on a plate 40 on the base at an 5 interval over the slide 3 and latch plate 36 in such relation to the latter that when the proper key is inserted in the barrel, a tongue 42 on the barrel trips the latch 36 against the action of the spring 37 whereby the slide 10 is retracted by the spring 4 and the switches are closed, while the closure 27 is free to be lifted as by its spring 43.

A casing 50 is not only secured by ordinary fastening means to the base 1 but is 15 also locked there when the slide is projected into latched position by a suitably arranged tongue 44 on the extension 25 that passes over a cross bar 45 of the casing and holds the latter against removal.

20 It is to be understood that the valve that is operated by the stem 26 may be of any form, whether with the valve closure herein shown or with a closure of other standard description. Preferably, however, the valve 25 casing has a detachable plug 46 that is screwthreaded into the lower end and carries a cage or strainer 47 on an apertured boss therein so that fluid passing up through the seat 48 on which the closure 27 rests 30 is forced to pass first through the screen and thereby prevent the entrance of solid matter into the fuel system.

Inasmuch as the spring 4 holds the slide 3 against the shoulder of the latch plate 36, and there is some lost motion necessarily, 35 a spring 50 of appropriate character is interposed between the slide 3, and a stop collar 51 on the plunger 26 of sufficient length to overpower the closure spring 43, 40 and thereby to hold the closure to seat. The collar 51 may act as a guide for the plunger in the sleeve 29.

The device as a whole is mounted on an appropriate part of the car, as for example, 45 a heel board 49 so as to be within easy reach of the person driving the car to throw the circuits open and close the fuel supply after stopping the car. The device is compact and effectively prevents movement of the car 50 under its motive power by persons who do not have means for releasing the slide from closed position while the car can be rolled out of danger in case of fire or shifted with ease as the clutches and other operative 55 mechanisms are not locked against such movement.

Obviously, changes in the details of construction may be made without departing from the spirit of my invention and I do 9 not care to limit myself to any particular form or arrangement of parts.

What I claim is:-

1. A safety device for automobiles com-

prising a pair of switches adapted to be connected respectively with the conductors of electric self starting and ignition systems, a valve for controlling the fuel supply of an automobile, a reciprocable member adapted when moved from initial position to open the switches and close the valve, means for 70 engaging the reciprocable member, a manually operable member adapted to contact with and move the reciprocable member into position for engagement with such means, a casing adapted to be locked in position to 75 house the mechanism by the reciprocable member when the latter is engaged by such means and permutation mechanism adapted when operated to trip the engaging means.

2. A safety device for automobiles comprising a base, switches mounted on the base and adapted to be connected with the conductors of electric self starting and ignition systems, a valve mounted on the base for controlling the fuel supply of an automobile, 85 a member reciprocable on the base adapted when moved from initial position to open the switches and close the valve, a latch plate for engaging the reciprocable member, a manually operable oscillatory member on 90 the base adapted to contact with and move the reciprocable member into position for engaging with the latch plate, a casing detachably mounted on the base over the mechanism and locked thereon by the controlling member when the latter is engaged by the latch plate, and permutation mechanism adapted when operated to trip the latch plate.

3. A safety device for automobiles comprising a base, a valve casing, a closure in the casing, a sleeve securing the casing and base, a plunger reciprocable through the sleeve for seating the closure, electric switches on the base, a controlling member 100 reciprocable on the base for operating the switches and simultaneously therewith depressing the plunger to seat the closure, a spring on the base for retracting the controlling member to initial position, a latch 105 plate swiveled on the base for locking the controlling member when the latter is fully projected, a manually operable oscillatory member on the base adapted to project the controlling member into engaged relation 110 with the latch plate, permutation mechanism for tripping the latch, and a casing detachably secured on the base and locked in position thereon by the controlling member when the latter is fully projected.

In testimony whereof I affix my signature in presence of two witnesses.
